PORTABLE PUMP

Franklyn G. Umholtz, P.O. Box 16G, Shutesbury, Mass.

Filed Feb. 27, 1961, Ser. No. 64,076

Term of patent 14 years

(Cl. D65—1)

FIGURES 3 and 4 are elevational views of the two sides of the pump;

The dominant feature of my design resides in the portions shown in full lines.

I claim:

The ornamental design for a portable pump, as shown and described.
